UNITED STATES PATENT OFFICE.

JOHN MURAT SHAWVAN, OF JANEVILLE, WISCONSIN, AND HARRY A. SHOLES, OF OAK PARK, ILLINOIS.

COMBINED PACKING AND DISPLAY CASE.

1,335,397.

Specification of Letters Patent. Patented Mar. 30, 1920.

Application filed August 30, 1919. Serial No. 320,933.

To all whom it may concern:

Be it known that we, JOHN MURAT SHAWVAN and HARRY A. SHOLES, citizens of the United States, residing, respectively, at 5 Janesville, in the county of Rock and State of Wisconsin, and Oak Park, in the county of Cook and State of Illinois, have invented certain new and useful Improvements in Combined Packing and Display Cases, of 10 which the following is a specification.

Our invention relates to a combined packing and display case which may be used for various purposes, but which is particularly adapted to be used as a packing and display 15 case for packages of flower or vegetable seeds.

Our invention contemplates a case of this kind provided with a series of removable trays adapted to hold a large number of 20 packages of seeds so that the trays may be stored away in the case in compact form for shipment or storage. The trays are arranged so that the retail merchant may display the goods by placing the trays one 25 above the other on suitable brackets, each bracket being formed with a series of steps. The packages bear pictorial representations of various flowers and vegetables, and in order to display the packages the trays must 30 be made shallow. The depth of the trays is usually less than one-half the height of the seed packages and when so constructed there is a space between the trays when they are placed on the brackets. In replacing the 35 packages, some of them are likely to slip through between the trays unnoticed and fall into the case where they are likely to remain until the trays are placed into the case for shipment or storage. The primary 40 object of our invention is to construct the trays so that the packages cannot slip through between them, which result preferably is accomplished by making the back wall of each tray approximately equal in 45 height to the height of the packages so that its upper edge is substantially even with the upper edge of the front of the tray just above it and providing the wall with clips adapted to engage the top edge of the front 50 wall of the tray next above, the clips on the highest tray engaging suitable hooks on the cover of the case or hooking over the edge

thereof. Moreover by so constructing the backs of the trays the insertion of packages taken out and afterward replaced is facilitated.

A further object of our invention is to provide in a case of this kind novel and improved constructions between the extremities of the trays and the supporting brackets 60 so that the trays will not tilt, but will be rigidly retained in proper position. When assembled on the brackets the trays are locked together and are preferably arranged so that they cannot be removed except in the 65 order in which they are placed on the brackets.

Our invention consists in the novel constructions, arrangements and devices to be hereinafter described and claimed, for carrying out the above stated objects, and such other objects as will appear from the following description.

The invention is illustrated in certain preferred embodiments in the accompanying 70 drawings wherein—

Figure 1 is a perspective view of a case embodying the principles of our invention, the seed trays being packed within the case;

Fig. 2 is a perspective view of the case, 80 the trays being removed and one of the supporting brackets being raised and locked to the cover of the case;

Fig. 3 is a perspective view of the case showing the trays placed on the supporting 85 brackets for display purposes;

Fig. 4 is a perspective view of one of the trays;

Figs. 5 and 6 respectively are sectional views taken on the lines 5—5 and 6—6 of 90 Fig. 3; and

Fig. 7 is a sectional view of the top tray showing the supporting clips thereof hooked over the edge of the cover of the case.

Like characters of reference designate like 95 parts in the several views.

The combined packing and display box comprises a box 10 provided with a cover 11 hingedly connected thereto, supporting end brackets 12, and a plurality of trays 13. 100 The supporting brackets 12 are preferably hingedly connected to the bottom of the box and are held in upright position by means of a hook 14 pivotally connected thereto and

adapted to engage the eye 15 secured to the cover 11. As shown on Figs. 1 and 2, the supporting brackets 12 are adapted to fold down against the bottom of the case so that 5 the trays 13 may be placed over the brackets when the case is to be shipped or stored away.

The trays 13, 13 are preferably constructed alike, both ends of each tray being provided with horizontal cleats 16 which are adapted to bear against the cleats 17 carried by the supporting brackets 12. The back wall 13^a of each tray extends upwardly to a height approximately equal to the height of 15 the packages of seeds.

The wall 13^a is provided with a plurality of clips 18 which are adapted to engage or slip over the top edge of the front wall of the tray next above as shown in Fig. 3. The 20 supporting brackets 12 are preferably provided with cleats 19 which are parallel to the cleats 17, the cleats 19 being omitted, however, from the lowest step, so that the lowest tray may be dropped into place. 25 Since the seed packages are of uniform size, the trays are preferably provided with thin dividing walls 20, thus providing a plurality of pockets in each tray.

The trays are arranged to display the 30 packages of seeds as follows: The top tray is placed so that the cleats 16 will slip in between the cleats 17 and 19 of the supporting brackets 12 and the clips 18 are hooked over the retaining member 21 secured to the cover 11. The second and third trays are placed on the brackets 12 in the same manner, the clips 18 of each tray engaging the top edge of the front wall of the tray next above. The last tray is then placed 40 down on the cleats 17 of the brackets 12 and the clips 18 carried thereon are hooked over the top edge of the front wall of the tray just above. When thus assembled the trays are securely retained in proper position on 45 the supporting brackets and are locked to each other. The cleats 19 make it impossible to remove the trays except by taking out the last tray first and the other trays in succession.

50 The case and trays may be made of any suitable material, but are preferably formed of sheet metal, the various cleats and clips being held in place by means of solder.

If desired, the retaining member 21 may 55 be omitted and the clips 18 carried by the top tray may be hooked over the edge of the cover as shown in Fig. 7.

The walls 13^a effectively close the gaps or 60 spaces between adjacent trays so that it is impossible for a package of seeds to slip through between the trays and fall into the case. If a package is taken out and afterward replaced it is quite natural to insert it 65 back of the other packages in the compartment where it belongs. When this is done

the back wall of the tray provides an unobstructed guiding surface, as it were, down which the edge of the package slips so that the replacement of the package is facilitated. With the ordinary arrangement of trays in 70 display cases of this type the back edge of the tray being below the tops of the packages contained in the tray will necessarily present an obstruction which may cause some inconvenience in replacing the packages and make it quite possible to slip a package between the trays and into the bottom of the case. 75

We claim:

1. A display case for seed packages and the like comprising a plurality of trays, upright members at the ends of the trays, and means thereon for supporting the trays so that they stand one back of and against another and at successively higher levels; the back walls of the trays being enough wider than the front walls thereof so that the upper edge of the back of each tray extends substantially to the upper edge of the front of the tray just above it, whereby the back 85 of each tray provides an unobstructed guide surface for facilitating the insertion of packages into the tray.

2. A display case for seed packages and the like comprising a plurality of trays, upright members at the ends of the trays, means thereon for supporting the trays so that they stand one back of and against another and at successively higher levels; the back walls of the trays being enough 90 wider than the front walls thereof so that the upper edge of the back of each tray extends substantially to the upper edge of the front of the tray just above it, whereby the back 95 of each tray provides an unobstructed guide surface for facilitating the insertion of packages into the tray.

3. A display case for seed packages and the like comprising in combination a box, having a hinged cover, stepped tray supports hinged to the ends of the box and adapted to be engaged with the cover when supports and cover are in vertical position, a plurality of trays adapted to be carried by said supports so that the trays stand one 110 back of and against another and at successively higher levels, the back walls of the trays being enough wider than the front walls thereof, so that the upper edges of the backs of the trays extend substantially to the upper edges of the fronts of the trays just above them respectively, and clips for engaging the back wall of the upper tray to said cover and the back wall of each other tray to the front wall of the tray just 115 above it.

4. A display case for seed packages and the like comprising in combination a box provided with a back member and end members, a plurality of trays, means for sup- 120

porting said trays on said end members so that they stand one back of and against the other and at successively higher levels, the back walls of the trays being enough wider than the front walls thereof so that said back walls extend up substantially to the upper edges of the front walls of the adjacent

trays respectively, means for engaging the back wall of the upper tray to said back member and the back walls of the other 10 trays to the front walls of the adjacent trays respectively.

JOHN MURAT SHAWVAN.

HARRY A. SHOLES.
